C. Schröder,

Bed Bottom.

N° 15,900.

Patented Oct 14, 1856.

UNITED STATES PATENT OFFICE.

CHARLES SCHRÖDER, OF NEW YORK, N. Y.

SPRING BED-BOTTOM.

Specification of Letters Patent No. 15,900, dated October 14, 1856.

To all whom it may concern:

Be it known that I, CHARLES SCHRÖDER, of New York, in the county and State of New York, have invented a new and Improved Spring-Bottom for Sofas, Bedsteads, &c.; and I do hereby declare that the following is a full and exact description thereof, reference being had to the accompanying drawings and to the letters of reference marked thereon.

The nature of my invention consists in the arrangement of spiral springs laying parallel to each other and horizontal under the seat or bedstead bottom. Each row being at the same time made of continuous wire and likewise connected together by a wire passing through the center of said springs. The whole being fastened to the frame, thereby forming an elastic bottom.

In the accompanying drawings A represents the frame of the bottom covered over by a covering B and lining C with the usual filling between the two. Under the lining C the spiral springs D lie horizontally. The same are made by being wound upon wooden blocks about 1 inch in diameter and about five (5) inches in length. The wire from one spring is then stretched to the other block the required distance of about six inches and then wound around this next block, and so on until the required length between one side of the frame and

the other side is obtained. By this arrangement the springs will of necessity require to be right handed and left handed. The ends are then passed through eyes (a) fast on the frames. A wire F is then passed through the centers of the blocks around which the springs are wound in such a manner as to connect the opposite ends of said springs, where the spring wire does not stretch from one coil of spring to the other, and the ends of said wire (F) are likewise fastened in eyes (a) attached to the frame, forming thereby a row of parallel situated springs connected together at both ends so as to form a band stretched from one side of the frame to the other. The advantage of this arrangement consists in the diminished space the springs occupy by this manner of construction making thereby this arrangement easy applicable for the use of the sides and back in sofas, chairs, &c., besides requiring a smaller quantity of hair or other fillings between the lining and covering.

What I claim as my invention is—

The arrangement of springs lying horizontally and connected together in the manner and for the purpose specified.

C. SCHRÖDER.
